OVER-CENTER SNAP SWITCH

Philip D. Grover, Two Rivers, Wis., assignor to Grover Products Corporation, a corporation of Illinois
Filed Apr. 9, 1964, Ser. No. 358,570
4 Claims. (Cl. 200—138)

This invention relates to over-center snap structure and, more particularly, to a device responsive to conditions such as temperature or humidity for effecting a snap action which is usefully employed as a means of switching an electrical circuit, as a circuit breaker for interrupting an electrical circuit, or for obtaining useful mechanical motion for opening valves and the like.

An object of this invention is to provide an over-center snap structure having a new and improved construction for more economical manufacture and more positive action.

Another object of this invention is to provide a condition-responsive, snap-action member which is simple and economical to manufacture.

Another object of this invention is to provide a thermally responsive snap switch in which the required snap action is developed essentially from a single annular stressed piece of bimetal for positive switching at a predetermined temperature.

Still another object of this invention is to provide a thermally responsive switching device as defined in the preceding paragraph with an unstressed compensating member which will maintain pressure on the electrical contacts thereof, right up to the point of snap, to effect a positive clean-cut switching action with no uncertain electrical continuity and changes of resistance which has been characteristic of most bimetallic thermostatic devices.

A further object of this invention is to provide a thermally sensitive pre-set temperature snapping switch which can have mechanical stresses manufactured therein overridden by an adjusting means so that the thermal switch will operate at temperatures required in varying applications.

A further object of the invention is to provide a condition-responsive actuator in which the actuator is formed as an annular member which is mechanically stressed to one concave configuration and with the member having condition-responsive material on the concave side thereof which expands at a greater rate than the remainder of the annular body to snap the body from one concave to oppositely concave configuration.

Another object of the invention is to provide an over-center snap structure having an annular body with mechanical stresses therein with the body being supported at a fulcrum point adjacent one part of the periphery of the body and actuating means engaging the body adjacent the other periphery with the fulcrum point and actuating means lying generally on a line which is a radius of the body to provide minimum twisting actuation of the structure.

A further object of the invention is to provide a simply and economically manufactured circuit breaking device utilizing an annular stressed bimetal member which can respond to an electrical overload by opening the circuit in which it is a component and which can either automatically restore the circuit after the overload condition is removed or the circuit can remain open until manually or mechanically reset.

Further objects and advantages will become apparent from the following detailed description taken in connection with the accompanying drawings in which:

FIG. 1 is a perspective view of an annular upwardly concave structure of bimetal with the high expansive material on top;

2

FIG. 2 is a perspective view of the structure shown in FIG. 1 mounted on a supporting structure and carrying an electrical contact together with the final position temperature-induced movement shown in broken line;

5 FIG. 3 is a perspective view of a preferred embodiment of the basic element with an unstressed compensating member projecting into the centrally disposed opening of the body;

10 FIG. 3A is a perspective view of a planar periphery mounted thermal snap element with a radially outward extending unstressed leg portion, serving here as an actuating member, and a radially inward extending member acting as a work take-off contact carrying member;

15 FIG. 4 is a vertical central section of the structure shown in FIG. 3 shown mounted illustrating how the compensating member tips the structure to offset the flattening effect of a temperature rise, or the like, on the position of the actuating part which would otherwise tend to be displaced downwardly;

20 FIG. 5 is a perspective view of an embodiment of the preferred thermal element in a snap switch structure with associated fixed electrical contacts;

25 FIG. 6 is a perspective view of an embodiment of the preferred thermal element in a snap switch structure adapted to change the requirements for causing actuation of the snap switch;

30 FIG. 7 is a perspective sectional view of an embodiment of the preferred thermal element in a circuit breaking structure, such as a typical household fuse, which will automatically reset itself;

35 FIG. 8 is a perspective exploded view of an embodiment of the preferred thermal element in a circuit breaking application, as a typical household fuse, containing a spring-loaded reset button to restore the circuit; and

35 FIG. 9 is a perspective view of another embodiment showing the minimal relation of fulcrum point and actuating means for the snap structure.

40 While this invention is susceptible of embodiment in many different forms, there is shown in the drawings and will herein be described in detail an embodiment of the invention together with modifications thereof with the understanding that the present disclosure is to be considered as an exemplification of the principles of the invention and is not intended to limit the invention to the embodiments illustrated. The scope of the invention will be pointed out in the appended claims.

45 The basic annular stressed disc is shown in FIG. 1. This disc is identified at 10. This disc is constructed of two layers of material, with one layer 12 being condition-
50 responsive material and the other layer 13 being spring metal. The condition to which the material 12 is responsive can either be heat or humidity. In order to be heat-responsive, the body would basically consist of bimetal and for humidity response, the layer 12 would be of a hygroscopic material, such as nylon, bonded to the layer 13. It is apparent that, since bimetal is a laminate of two metals with different rates of expansion, the application of heat will cause the higher rate of expansion metal 12 to expand more in all directions than the low expansion metal 13. This manifests itself well in an annular unstressed disc which expands from an essentially planar structure at ambient temperature to a form that may be considered as embracing a portion of a sphere. While the more familiar form of a strip of bimetal bends along its axis, it is often overlooked that bending takes place in all directions.

55 As taught in my prior patent No. 2,861,143, planar spring material may be stressed out of its planar form by shortening a portion of its periphery with a wave or corrugation, so that the material may be considered to lie on a spherical surface.

The stresses which are introduced by mechanical deformation of the structure are "mechanical" stresses, and those stresses which temporarily deform or bend the bimetal may be called "thermal" stresses. In the final analysis at any given moment in the movement of the device, the stresses are essentially of the same quality. The difference is that the mechanical stresses do not vary with a condition, such as heat, while the thermal stresses are a function of the temperature of the device.

The annular disc 10 as shown in FIG. 1 has been mechanically stressed by shortening a portion of its periphery, as by a corrugation 11. This deformation results in an upwardly concave structure with the high expansive material 12 on the upper side of the disc. This spring metal layer 13 is on the lower side of the disc. The application of heat to the structure will result in thermal bending forces radially acting to overcome the mechanically-induced stresses. At a certain point in the temperature rise, the thermal stresses will overcome the mechanical stresses and cause the member to snap inside-out. Similarly, the same action would occur in a humidity-responsive construction.

With a decrease in temperature from the upper temperature reached, the thermal stresses causing the bimetal to bend are lessened and finally reach the point where the mechanical stresses in the spring-like disc member overcome the diminishing thermal stresses and the device returns to its original position with a snap action.

When the disc 10 is first stressed mechanically out of its essentially planar form, a bias may be introduced, as by permanently bending the periphery of the body, to accentuate or diminish the mechanical stresses holding the disc in a concave form. This bias may be of such magnitude that, once forced over center, the disc will not return to its original position. Or again, the bias may be such that it takes very little pressure to snap the disc over center. In the preferred practice, the biasing is achieved by bending the metal on one side of the corrugation to a greater or lesser angle relative to that on the other side.

The amount of mechanical stressing of the annular disc is a function of the amount of foreshortening which in turn is a function of the amount of material drawn into the corrugation 11.

In FIGURE 2, the basic disc 10 is mounted at one portion of its periphery on a mounting 14 and has an electrical contact 15 at another portion of its periphery. This structure may be considered as a thermal functioning element of an electric snap switch when suitable fixed contacts are positioned to engage the electrical contact on the disc.

For best use as an electrical switch, it is necessary to have the movable contact in pressurized engagement with the fixed contact to permit the current to flow through the junction effected. The action of the disc 10 is improved by use of a bimetallic compensating member which is essentially unstressed mechanically. This structure is shown in FIG. 3 in which an annular disc 20, similar to disc 10, with a corrugation 21 has an unstressed compensating member 22. With the structure mounted on a post 23 by the compensating member, as shown in FIG. 4, the compensating member can bend in a direction to tilt the whole structure as it tends to flatten out with the application of heat. The movable contact 24 remains in pressurized contact with a fixed contact.

Sufficient length of stock to form the compensating member can be obtained from within the opening of the annular disc. The same effect could be obtained with a separate bimetallic support outside of the annular disc or the supporting portion could be blanked from the same piece of material. A separate compensating member used as a mounting means may be utilized in a configuration where it extends radially outwards from the stressed member providing the high expansive side of this compensating bimetal member is opposite the high expansive side

of the stressed member so that it will tilt the stressed member to offset the flattening effect of the stressed member, as a change in environment causes the stressed element to approach the snap point. Thus, an electrical contact diametrically across the stressed member from the support point can maintain or even increase its pressure on the fixed contact prior to snap.

This unstressed member 22 can be used as a mounting and thus compensates, as shown in FIG. 4, or can be used as an actuating means or a mechanical power take-off. When used as a mounting, the compensating member does not interfere with the action of the stressed disc. If the unstressed member extends radially to the outside it provides a large displacement relative to the displacement of the periphery of the disc 20. This extension can be used as a work take-off member, or as an actuating member. It then would not serve as a compensating mounting means, as in keeping a movable contact in pressurized conjunction with a fixed contact to offset the flattening effect of the concave disc prior to snap, but would enhance this "lift-off" effect. When the member 22 is used as an actuating means, a downward actuating force will snap the structure up or down depending on whether the compensating member is positioned inside or outside the disc. As a mechanical take-off, the integral unstressed member can provide a larger displacement when extending from the exterior of the disc than if within the interior of the disc, as it is limited by the length of the opening in the structure.

FIG. 3A shows a peripherally hinged snap unit 25 similar to disc 20 with a radially extending internal unstressed member 26 and a radially outward extending member 27, either of which can be used as an actuating member to twist the periphery and effect a snap, or as a work take-off member as to snap a movable contact to engage a fixed contact. In this example there is no compensating function. A plurality of posts 28 with notches 29 support the disc at its periphery.

A complete switch utilizing the structure of FIG. 4 is shown in FIG. 5. As shown in FIG. 5, a stressed annular disc 30 of bimetal constructed similarly to disc 20 shown in FIG. 4 has an unstressed compensating member 31 by which the disc is mounted to a mounting post 32 and a base 33a of dielectric material. A central common terminal 33 has a pair of flexible leaves 34 and 35, each of which carry a contact 36 and 37, respectively. A leaf 38, carrying a contact 39, forms, with the contact 36, a normally closed circuit.

When the temperature reaches a sufficient level to have the thermal stresses overcome the mechanical stresses, the disc 30 snaps to an oppositely concave configuration to release the engagement between contacts 36 and 39 and cause a contact 37 on the leaf 35 to engage a contact 41 on a leaf 42 of the normally open side of the circuit. Each of the leaves 38 and 42 are secured to an insulating mounting by means of rivets, such as indicated at 43, and each of the leaves has a terminal screw, as indicated at 44 for the leaf 38. This switch can sense the surrounding air temperature and respond with a snap action to switch an electrical circuit at a predetermined temperature. Also, the switch can be used to sense the temperature of an object, such as a container being heated, by having a thermally-conductive path through the base 33a to the disc 30. The thermal conductivity of a base when formed of metal is superior to that of air, so as to increase the sensitivity of the unit. In such instances where electrical shock would be a hazard, the disc 30 can be removed from the circuit and solely used as an actuator to move the necessary contacts, as through an insulating actuating member, 40.

FIG. 6 shows another embodiment of switch in which it is possible to change the temperature at which the unit will snap. As stated previously, the bimetal responds to heat to exert stresses which can overcome the mechanical stresses to shift the disc of material to an opposite concave configuration. If the mechanical forces to be over-

come are increased, it will require more of a temperature change to accomplish this. Conversely, if the mechanical forces are lessened, a lesser change in temperature will be required. In the switch shown in FIG. 6, a disc 50, similar to disc 30 shown in FIG. 5, is mounted by a compensating member 51 on a heat conductive, metal mounting post 52 having a base 53 which can provide a high conductive path for heat. A series of three leaves 54, 55 and 56 are mounted on the base 53 by an insulating mounting block 57 and each has an electrical terminal 58, 59, and 60, respectively. An insulating button, 70 on disc 50 may be used to keep the members 50, 51, 52 and 53 electrically isolated from the switching elements where metal is used as a high heat transmission material in the disc supporting elements. The leaves 54 and 55 are sprung to move downwardly toward the base 53 and the actual position of leaf 54 is determined by a threaded shaft 61 having a manually-operable knob 62 and engageable with an insulating pad 63 on the base 53. This threaded shaft is threaded into the upper leaf 54 whereby the position of the leaf 54 from the base 53 can be determined by the rotative position of the shaft. Leaf 55 is biased down so that contact 67 will engage contact 68, when the pressure exerted by disc 50 is released by snapping over center.

With the disc 50 in its concave configuration, as shown in FIG. 6, the contacts 65 and 66 on the leaves 54 and 55 are in contact as maintained by the disc 50. With an increase in temperature, the disc 50 snaps over center and the contact 67 on leaf 55 moves into engagement with the contact 68 on the leaf 56 by virtue of the downward bias of leaf 55. This structure illustrates the primary principle in modifying the total mechanical forces involved in the switch. The leaf 54 through the adjustment shaft 61 determines the upper position of the annular disc 50 so that this disc may not move upwardly to its final position and thus less thermal stresses to overcome the mechanical stresses are required to snap the structure over center. It is thus possible to vary the temperature at which the switch will respond.

Another use of the annular stressed disc of bimetal is shown in FIG. 7 in a circuit breaking application, such as a household fuse. With the conventional threaded body 70, a conducting portion 71 has a conducting post 72 to which a compensating member 73 is attached and mounts the annular disc 74 similar to disc 20. The disc 74 carries a contact 75 engageable with a contact 76 associated with the conductive casing of the fuse 77. As shown in FIG. 7, the annular disc 74 is in an upwardly concave configuration, with the high expansion material on the underside with the fuse open. In this instance, the disc 74 is formed of material and proportioned so that the resistance of the unit when encountering an electrical overload will cause it to be heated by its own resistance until sufficient thermal stresses are built up to effect an overcoming of the mechanical stresses and the unit snaps over center to the position shown. In normal usage, the disc 74 would be in its downwardly concave configuration, with the contacts 75 and 76 in engagement. In this embodiment, the unit is self-restoring. Once the disc 74 cools, the circuit would be reestablished and would be maintained closed so long as there is no electrical overloading. In practice, an electrical resistance element such as nichrome wire may be located in close proximity to the thermal snap element, (73 and 74), and connected electrically in series with the thermal snap element to augment the heating effect of current flowing through the resistance of the bimetal from which the disc is made. This additional heat would improve the response time and the sensitivity of the device.

In the embodiment of FIG. 8, which is also a circuit breaking application such as a household fuse, the structure is generally the same as that shown in FIG. 7 in which a disc 80 is mounted on a conductive post 81 by a compensating member 82 with the disc carrying a con-

tact 83 engageable with a contact 84 associated with a conductive exterior of the fuse. The parts being shown in FIG. 8 open after an overload. In this embodiment, bias has been placed in the disc 80 so that the disc 80 will remain in its snapped-over configuration even after cooling. In order to re-set the fuse, it is necessary to mechanically shift the disc 80 to a downwardly concave configuration as accomplished by depression of a plate 87 fitting under an enclosing cover 88 having a plunger 89 extending through an opening 90. The plunger 89 can be manually depressed against a spring 91 to have a lug 92 engage a raised portion 86 of the disc and snap it, by prying against a downturned portion 85 of the disc which acts as a fulcrum, thus twisting a portion of the periphery of the disc to effect a resetting snap switch action.

In FIG. 9, an annular disc 100, with compensating member 101 formed of stressed bimetal similar to those previously described, is disclosed in which the disc can be mounted on a post 102. In this embodiment, a fulcrum 103 on a supporting structure is provided in contact with the disc 100 closely adjacent the inner periphery thereof and a movable actuating member 104 is provided adjacent the outer periphery of the disc. A line extending between the fulcrum 103 and the actuating member 104 where it engages the disc lies generally along a radius of the annular member. This is a construction in which the basic action in obtaining a snap of the annular member is accomplished by applying a minimum actuating displacement between the fulcrum point and the point of actuating force. This structure utilizes a minimum actuating movement differential.

As will be seen from the foregoing description, the basic shape of the bimetal disc is that of an annulus which inherently, upon a change or increase in temperature from the ambient temperature, will assume a shape to embrace a spherical segment. This approximate same shape is also induced by the shortening corrugation, as formed in the disc. The increase in temperature exerting the thermal stresses causes lines of radial force to impart a twisting action to the periphery or body of the disc to overcome the mechanical stresses. This follows the natural action of the bimetal disc and achieves the desired snap action most efficiently. If the configuration were other than annular, such as triangular or rectangularly elongate, the bending forces induced by a given temperature rise attempt to make the piece move to embrace a spherical configuration which is not that which the part is shaped to take, so that a substantial portion of the forces would be used ineffectively.

50 I claim:

1. A thermal responsive snap switch comprising, a heat conducting base, an annular body of bimetal, a wave in said body inducing an initial stress and concave configuration therein, an unstressed compensating member extending inwardly from the periphery of the body defining a mounting for said annular body, a heat conducting member extending from the base on which the compensating member is mounted, a stationary contact and a movable contact, heating of the body causing over-center movement of the body to change the relation of said contacts, a leaf carrying said movable contact and engageable by said annular body.

2. A snap switch as defined in claim 1 and having means for adjustably limiting the movement in one direction of said leaf and correspondingly limiting the movement of the annular body in the same direction.

3. A snap switch structure responsive to ambient conditions comprising a base for mounting of the switch components, a fixed switch contact supported by said base, a movable switch contact selectively engageable with the fixed contact, and means carrying said movable contact including an annular body formed of spring metal with an interior opening and said body having a wave at one location along the length thereof to introduce mechanical stress into the body and place said body in a

concave configuration, an integral unstressed compensating leg extending inwardly into said opening, fastener means adjacent the end of said leg attaching the leg to said base with the contacts in engagement and a layer of hygroscopic material on the concave side of the body and the same side of said leg whereby a change of condition acts to bend the leg to maintain the contacts in engagement until the change is of a magnitude to create a force overcoming the mechanical stress in said body and shift said body over-center to disengage said contacts. 5

4. A condition responsive snap switch comprising a base, an annular body of condition responsive material, a wave in said body inducing an initial stress and concave configuration therein, an unstressed compensating member extending inwardly from the periphery of the body 15 defining a mounting to the base for the body adjacent a free end of said member, a stationary contact and a movable contact, a leaf member carrying said movable contact and extending to a position for selective engagement by said body whereby the body in snapping 20 over-center shifts the leaf member to change the relation of the contacts, and adjustable means directly in line

with said leaf member contact and in back-up engagement therewith for limiting the movement in one direction of said leaf member and correspondingly limiting the movement of the annular body in the same direction. 10
